Jackson, J., The Modern Guide to Golf Clubmaking, 1987, p. 237,
Dynacraft Golf Products, Inc., Newark, Ohio, USA.*Primary Examiner* — Mitchell Siegel(74) *Attorney, Agent, or Firm* — Randy K. Chang(57) **CLAIM**

The ornamental design for a wedge golf club head, as shown and described.

DESCRIPTION

FIG. 1 is a perspective view of our new wedge golf club head;
 FIG. 2 is a back view thereof;
 FIG. 3 is a top view thereof;
 FIG. 4 is a bottom view thereof;
 FIG. 5 is a heel view thereof;
 FIG. 6 is a toe side view thereof; and,
 FIG. 7 is a font view thereof.

The broken line showing on the striking face is included for the purpose of illustrating and forms no part of the claimed design.
